UNITED STATES PATENT OFFICE.

D. HENWOOD AND J. STEPHENS, OF BROOKLYN, NEW YORK, ASSIGNORS TO THEMSELVES
AND THOS. F. ROWLAND, OF SAME PLACE.

MACHINE FOR HULLING AND CLEANING RICE.

Specification of Letters Patent No. 20,971, dated July 20, 1858.

To all whom it may concern:

Be it known that we, DAVID HENWOOD and JAMES STEPHENS, both of the city of Brooklyn, in the county of Kings and State 5 of New York, have invented a new and useful Machine for Hulling, Scouring, and Cleaning Rice and other Grain; and we do hereby declare that the same is described and represented in the following specifications and drawings.

To enable others skilled in the art to make and use our invention we will proceed to describe its construction and operation referring to the drawings in which the same 15 letters indicate like parts in each of the figures.

Figure 1, is a sectional elevation in which most of the parts are represented as cut lengthwise through the center of the machine. Fig. 2, is an elevation of one end. Fig. 3, is an elevation of the hulling cylinder full size; and Fig. 4, a section of the same, and Fig. 5, a plan of the top.

The nature of our invention consists in a 25 rotating cylinder, with spiral wedge shaped grooves in its periphery, including outward and downward, surrounded by a cylinder lined with india rubber, or some yielding substance, which is not hard enough to break 30 much if any of the grain, as it is rolled down around the cylinder, in the V shaped spaces between the cylinder and the india rubber that surrounds it and hulled; the small kernels sink deeper in the V shaped 35 spaces, so that they are rolled, and hulled, with nearly the same pressure, that the large ones receive. And in making one or more large grooves around the hulling cylinder or in the stationary lining, so as to let 40 the kernels of grain escape from one groove as they descend, and enter another in a different position, so as to be more efficiently rolled and hulled, than if they descend without this chance of changing position. Also 45 in making the top of the cylinder convex, or conical with curved wedge shaped grooves, and covering it with india rubber, or some substance that will yield so as not to break much of the grain, as it aids in 50 hulling it. Also in the use of two scouring cylinders, one within the other turning in opposite directions; the inner one covered with wire card clothing, to act upon the grain and scour it, in conjunction with the 55 burs on the inside of the perforated sheet

metal cylinder, while most or all of the substances scoured from the grain, are thrown through the perforations in the outer cylinder. Also in a fan to separate the hulls from the grain between the hulling and 60 scouring cylinders.

In the accompanying drawings A, is one of the front posts, A', one of the middle posts and A², A², the rear posts connected together by the bar B, girders B', B', B', 65 and top rails B², B², B² forming a strong frame to which most of the other parts are fastened or connected. The top rails B² may be connected by two bars like C, and the frame strengthened by braces C', C'. 70

D, is a cast iron conical cylinder, with a flange at its lower and smallest end, large enough to cover the opening between the rails B², and bars C', to which it is fastened in the position shown in the drawing. The cylinder D, has a circular flange at its upper end to which the concave cap D' is fitted and fastened; which cap D', projects down into the top of the cylinder D, to press the india rubber lining D² down against the 75 flange on the inside of cylinder D, at the bottom, so as to hold said lining firmly in its place. The cap D', is made in the form shown in the drawing, with a hollow inverted cone projecting down from the top which receives the grain from the hopper E, 80 through the openings E', in the cap, which openings are made largest on the lower side, so that the rice or grain may not clog in descending from the hopper E, into the inverted cone E³, which conducts it onto the top of the hulling cylinder F, provided with curved wedged shaped plates as shown in 85 Figs. 3, 4, and 5, which force the grain out, as the cylinder is turned under the india rubber lining of the disk E², which aids in 90 hulling it. The disk E², is made with a flange at each edge to hold the india rubber lining as shown in the drawing; and it is 95 adjusted and held at the desired height by the screws G, G, in the cap D'. 100

There is a lug on the top of the cap D', which is perforated from the under side for the end of the shaft F', to turn in; the lower end of said shaft, turns in the box F², fastened to the base or floor. The shaft F', is turned by the gear G', acted upon by the gear G², on the shaft H, which turns in boxes on the girders B', B', and may have 105 a pulley, gear or crank applied to it, by 110

which it may be turned to operate the machine. The shaft F', has a screw thread on it near its upper end to which the female screw in the cylinder F, is fitted, so that by turning the cylinder, (which is made conical), it may be raised or lowered to increase or diminish the space between the outside of the cylinder F, and the india rubber lining D², of the cylinder D, and 10 adjust the space to suit the size of the kernels of rice or grain being hulled: and when so adjusted it may be firmly fastened to the shaft by the set screw H'.

The outside of the cylinder F, is scored 15 or grooved spirally as shown in Fig. 3. These scores are about one third of an inch wide, and one eighth of an inch deep, the upper side of the score is at a right angle to the surface of the cylinder, while the lower 20 side inclines from the upper side outward, as shown in the drawing. We have found these cylinders to work well, and do good service, when the spiral grooves were made to rise at about an angle of seventeen degrees 25 from the base of the cylinder; and we think it an advantage to make a groove H², around the cylinder about half way between the top and bottom large enough for the grain to escape from the flutes or spiral 30 grooves, and enter others in the lower portion of the cylinder, in a different position, so as to be more effectually acted upon, than if they passed from the top to the bottom of the cylinder, in the same groove. The rice 35 is rolled in the V shaped spaces, between the hard cylinder and the yielding lining and hulled; the small kernels sink deeper in the V shaped spaces, and are rolled with nearly the same pressure that the large kernels receive, which is a great advantage. The rice 40 or grain after descending from between the cylinder F, and lining D², falls on the inclined board I, shown by dotted lines in Fig. 2, from which it falls through the blast of 45 the fan I', into the inclined trough I², which conducts it into the end of the scouring cylinder as shown in Fig. 1, the hulls and all the light substances being separated from the grain by the blast from the fan I, and 50 blown out of the machine before the grain enters the scouring cylinder. The fan I, is arranged to turn in boxes fastened to the posts A, and A', and is turned by the band J from the pulley J' on the shaft H, to the 55 pulley J² on the fan shaft.

The outside scouring cylinder K, is made of perforated sheet metal; the lower portion of this cylinder is represented as broken away to show the inside scouring cylinder L. 60 Both of these cylinders are made conical and arranged to receive the grain from the trough I², between them at the smallest end. We prefer the cylinder K, made of sheet steel, perforated with a sharp punch, either 65 round or of some other form, so as to raise a

bur on the inside to aid in scouring the grain; it may be made in two parts and joined by a hinge joint, as shown at K', and the ends fastened to the disks K², and K³, which disks are made in the form shown in 70 the drawing, with long hollow journals projecting from them, and fitted to turn in the boxes on the girders B', B', Fig. 1. The disk K², has a flange M, extending from it and turning in toward the shaft to receive the 75 grain from the trough I², and it passes from the flange M, through the holes in the disk, one of which is shown at N, into the cylinder K, where it is scoured, as it passes along 80 between the cylinders K, and L, which revolve in opposite directions, and then escapes from the cylinder through the hole N', in the disk K³, and falls into the trough N², which conducts it out of the machine. The journal of the disk K³, extends through the 85 box and has the pulley P, fastened to it by which the cylinder is turned in the direction of the arrow a, by a band from the pulley P', on the shaft H.

The shaft L' of the cylinder L, is fitted 90 to turn in the hollow journals of the cylinder K, and has the pulley R, fastened to it, to turn it in the direction of the arrow b, and in the opposite direction to the cylinder K, by a band from the pulley R', on the 95 shaft H. The cylinder L, is covered with fine wire card clothing, such as is used for carding cotton and wool, which wire teeth act on the grain, in conjunction with the bur, on the inside of cylinder K, and scour 100 the grain; and as the cylinders both revolve in opposite directions the grain is uniformly spread between them and prevented from settling to the lower side; while the centrifugal force with the blast of air which 105 is constantly escaping through the perforations in the cylinder K, carries out through these perforations most, or all of the matter or substances scoured from the grain, leaving it nearly or quite clean. 110

The machine having been constructed as above described and set in motion the rice is supplied to the hopper E, and passes down onto and around the cylinder where it is rolled in the V, or wedge shaped space between the groove in the rotating cylinder and the yielding india rubber lining of the stationary one, which india rubber lining is firm enough to remove the hulls, and yielding enough not to break much if any of the grain: which after it escapes from the huller falls through the blast of air from the fan I, which separates the loose hulls, chaff and other matter lighter than the grain, which grain descends in the trough I² and passes into the cylinder K, through the holes N, where it is scoured by the action of the two cylinders and most of the scourings are thrown through the openings in the cylinder K, and the scoured and cleaned grain es- 120 125 130

capes through the holes N', into the trough N² that conveys it out of the machine.

Our machine is much superior to those heretofore made, requiring less attention to 5 operate it, as it is not liable to choke, and far less liable to get out of order or want repairing, being far more durable and requiring far less power to operate it, in proportion to the amount of grain cleaned. 10 Besides it is twenty five per cent cheaper, and will do fifteen per cent more work, and make fifty per cent less broken rice than any machine within our knowledge.

We believe we have described and represented the machine, which we have invented, for hulling and cleaning rice and other grain, so as to enable any person skilled in the art to make and use it, we will now state what we desire to secure by Letters Patent; to wit,

We claim—

1. The cylinder F, provided with wedge shaped spiral grooves inclining outward and downward, substantially as described, 25 in combination with the stationary india

rubber lining D², or such equivalent lining, that is firm enough to hull the grain, and yielding enough not to break much of it in the process of hulling.

2. We also claim making the top of the 30 cylinder F, convex or conical, with curved wedge shaped grooves as described, in combination with the stationary adjustable disk above it, lined with india rubber gutta percha, or some equivalent substance for the 35 purpose set forth.

3. We claim a cylinder covered with wire card clothing, in combination with a cylinder of perforated sheet metal, when both are made to revolve in opposite directions, for 40 the purposes set forth.

4. We claim the huller covered by the first claim, in combination with the scourer covered by the fourth claim, arranged and operating as herein described.

DAVID HENWOOD.
JAMES STEPHENS.
